12 Claims. (Cl. 51—52)

1

This invention relates to machines for grinding the teeth of gear wheels, of the kind in which a formed grinding wheel is reciprocated between the tooth surfaces, and the toothed wheel is intermittently rotated to bring successive tooth faces under the action of the grinding wheel, the latter being trimmed periodically to maintain its form. The object of the present invention is to enable the feed movements of the workpiece relatively to the grinding wheel, and also the determining of the wheel trimming periods, to be effected automatically.

The invention comprises the combination with a headstock, a side movable vertically in the headstock, a work spindle carried by the slide, a manually operable screw for moving the slide in the headstock, and an index-plate carried by the work spindle of an intermittently operable feeding mechanism for imparting feed movements to the slide independently of the said screw, means consisting in part of an electromagnet for actuating the feeding mechanism, and means responsive to rotational movements of the work spindle for controlling the said electromagnet.

The invention also comprises the combination with the feeding mechanism, of electrical contact devices for determining the grinding wheel trimming periods.

In the accompanying sheets of explanatory drawings—

Figures 1 and 2 are respectively side and end elevations of a known form of gear wheel grinding machine having the invention applied thereto.

Figure 3 is a sectional side elevation and Figure 4 a sectional end elevation of a mechanism embodying the invention.

Figure 5 is a plan illustrating the mechanism with portions broken away to disclose certain of the electrical contact devices.

Figure 6 is a plan illustrating the mechanism for imparting feed movements to the work piece.

Figures 7 and 8 are respectively sectional side elevations in planes at right angles to each other of the mechanisms shown in plan at Figures 5 and 6.

Figures 9 and 10 are detail views of certain elements to be referred to hereafter.

To facilitate explanation of the invention, a brief description will first be given of the machine illustrated by Figures 1 and 2, the larger part of this machine being already known. On the bed *a* is arranged a slide *b* which is adapted to be reciprocated horizontally on the bed *a*. The slide carries a rotary grinding wheel *c* the periphery of which is shaped to conform with the

5 adjacent flanks of a pair of wheel teeth. Associated with the headstock *d* is arranged a spindle *e* which carries the toothed wheel to be ground, the latter being herein referred to as the work piece. The spindle *e* is carried by a slide which is movable vertically between guides in the headstock. This movement can be effected manually by a hand operable member *f* engaging a screw *g*. Intermittent angular movements are given to the spindle *e* to bring successive tooth spaces opposite the grinding wheel, and these movements are imparted by a known mechanism which includes a peripherally notched index plate to be referred to again hereafter. Also on the bed of the machine is arranged a known form of trimming mechanism for periodically truing the operative parts of the grinding wheel, this mechanism being indicated generally by *h* in Figure 1. The mechanism forming the subject of the present invention is arranged for the greater part in association with the headstock *d*.

Referring now to Figures 3 and 4 which illustrate the headstock *d* more fully, the work spindle *e* is carried as already stated by a slide *i* movable between guides *k* in the headstock, and at the rear end of the spindle *e* is secured the peripherally notched index plate *l*. This plate is given intermittent angular movements by a known mechanism which forms no part of the present invention and which has been omitted from the drawings to avoid undue complication. The source of motion of this plate is a shaft *m* (Figure 1) which serves to actuate a pawl engaging the notches of the index plate, the pawl being located in the housing *n* (Figure 2). Ordinarily the feed screw *g* is directly connected at one end to the slide *i*, but for the purpose of my invention it is attached to a connecting piece *o* which in turn is connected by a link *p* to a forked crank arm *q*. The link is pivotally attached at its ends to the piece *o* and the crank arm respectively. The crank arm is pivotally attached to the slide *i* in the manner clearly shown in Figure 4, and the pivot axis of the crank arm 45 is eccentric to the adjacent pivot axis of the connection between the link *p* and the crank arm *q* as is also clearly shown in Figure 4. The arrangement is such that the slide can be raised and lowered to any desired position by manual 50 operation through the medium of member *f* and the screw *g*. The member *f* is carried on the headstock and consists in part of a nut engaging the screw. But the feed movements are imparted to the slide by the crank arm independently of the screw through a range which is de-

terminated by the eccentricity of the two pivot axes above mentioned and which is made sufficient to allow the work piece to be fed relatively to the grinding wheel by the amount corresponding to the amount of material to be removed from the work piece by the grinding wheel. The actuation of the crank arm is effected automatically in the manner which will now be described with particular reference to Figures 3, 4, 6, 7, and 8.

Alongside the headstock is mounted a housing *r* herein referred to as the control box. In the control box is mounted a spindle *s* which at its upper end has secured to it a dial *t* operable by a handle 6 (Figures 1, 2 and 4) enabling the spindle *s* to be actuated by hand when required, and on the housing is secured a pointer *u* (Figures 1 and 2) for assisting the user to set the dial to any desired position. On the spindle *s* is secured a pinion *v* which engages a slidable rack *w* one end of which is pivotally connected by a link *x* to the crank arm *q* (Figure 3), enabling feed motions to be imparted to the crank arm and thence to the workpiece, either by hand or automatically. To effect automatic actuation there is also secured to the spindle *s* a peripherally notched disc *y* (see Figure 6) and in association with this disc there is pivotally mounted in the control box an arm 2 which carries a pivoted pawl 3 loaded by a tension spring 4 which tends to hold one end of the pawl in engagement with the disc *y*. In addition there is pivoted in the control box a retaining pawl 5 which is loaded by a blade spring 7, the purpose of this pawl being to prevent reverse rotation of the notched disc. To enable both pawls to be put out of action when it is desired to be able to rotate the disc by hand in either direction, a rotatable cam 8 (Figure 6) is arranged in the control box in association with a pair of adjacent ends of the two pawls, this cam being rotatable by a handle 9 (Figure 5). Automatic actuation of the arm 2 is effected in one direction by a solenoid 10 and in the other direction by a spring 11. The arm is connected to the movable core of the solenoid by a link 12, and this link is also connected to a tube 13 which can slide on a fixed guide bar 14, the spring 11 being located within this tube as shown in Figure 6. The solenoid serves to effect retractive idle movements of the arm 2 and pawl 3 relatively to the notched disc *y*, and the spring 11 serves to impart the required feed movements to the disc *y* through the said arm and pawl. An adjustable stop 15 carried by the control box serves to limit the operative movements of the arm.

The control of the supply of electric current from any convenient source to the solenoid is effected by the index plate 1. On this plate is secured a striker 16, which at the end of each complete rotation of the index plate, engages a lever 17 (Figures 7 and 9) and by lifting this lever causes it to raise a plunger 18 which lifts a movable contact piece 19 into contact with a pair of resilient contacts 20 which may be loaded by springs 21 (Figure 9), so closing the solenoid circuit. The effect of this is to bring the solenoid 10 into action, causing the arm 2 and pawl 3 to be retracted against the action of the spring 11, and to hold the said parts in their retracted position. When the index plate 1 begins its next rotation the striker 16 leaves the lever 17 and allows the contact pieces to resume their initial positions, thereby causing the solenoid circuit to be reopened. Whereupon the spring 11 imparts a feed movement to the work piece, the above described action being repeated after each com-

plete rotation of the index plate until the grinding operation has been completed.

The angular movement given to disc *y* in each action is constant, but the feed movement given to the slide *i* progressively diminishes as the crank arm *q* approaches the central or vertical position. Consequently at the commencement of a grinding operation on the work piece the feed movements are relatively coarse, and they become progressively finer towards the completion of the grinding operation. The total step-by-step movement required to be given to the disc *y* for moving the crank arm *q* throughout its range of movement (which corresponds to the total feed movement to be given to the slide *i* for a given work piece) is usually a little less than one revolution.

During the grinding operation it is necessary to trim the grinding wheel at appropriate intervals, and to enable these periods to be determined automatically, we provide on the dial *t* of the control box, a series of suitably placed and externally projecting radial striking pieces 23 (Figures 5 and 7). These are not equally spaced, but are so disposed that the time intervals between successive trimming actions are longer during the initial stages of the grinding operation when what may be termed coarse grinding occurs, than in the later stages when the fine or finishing grinding occurs. The striking pieces 23 are brought into action successively during the rotation of the dial *t* by the spindle *s* to which is secured the notched disc *y* above described. The particular machine to which the invention is shown applied is ordinarily fitted with a mechanism controlled by a hand lever 24 (Figure 1) by which the grinding action can be temporarily arrested. The slide *b* is caused to be retracted so as to bring the grinding wheel *c* to the trimming mechanism *h* by a further lever (not shown). In association with this mechanism we arrange any convenient electromagnetic means such as a solenoid (not shown) which when excited serves to perform the same function as the said levers, and this solenoid is arranged in a circuit which is controlled by a switch operable by the strikers 23. The switch (see Figure 5) comprises a pair of contacts 25, 26 and a pivoted contact member 27 loaded by a spring 28 which tends to hold the part 27 on the contact 25. The contact member 27 is movable in opposition to the spring on to the contact 26 through a plunger 29 by any one of the strikers 23. The contact 25 is in series with the circuit containing the feed solenoid 10 above described, and the contact 26 is in the circuit of the solenoid above mentioned associated with the controlling means of the trimming mechanism. When any of the strikers 23 reaches the plunger 29 it causes the latter to move the member 27 so as to open the circuit of the solenoid 10 (and thereby put the feed mechanism out of action) and close the circuit of the other solenoid through the contact 26. This latter solenoid now performs the function ordinarily effected by one of the above mentioned levers and the slide *b* is caused to move to the wheel trimming position. The trimming operation is then performed in the usual manner either under the control of the attendant or automatically, and on completion of this operation the attendant restarts the machine in the usual manner by actuation of the usual means such as a push button switch on the control panel 30. But it is also necessary at the same time to bring the feed solenoid into action again by restoring the switch (25, 26, 27) to its initial

condition. To enable this to be effected, I mount the plunger 29 on a pivoted arm 31 (Figures 5 and 10) loaded by a spring 32, and the arm 31 is connected by a link 33 to the core 34 of a solenoid 35 situated in the control box. The circuit of this solenoid is controlled by a switch 37 (Figure 1) which is operable by a tappet 38 on the slide b. When the slide returns in the usual manner to the working position after the wheel has been trimmed the tappet 38 knocks the switch 37 over from one of its limit positions to the other, and during this movement the circuit of the solenoid 35 is momentarily closed causing the solenoid core to pull the arm 31 to the left (Figures 5 and 10) and so carry the plunger 29 away from the striker with which it was previously in contact. The part 27 now returns under the action of its spring to the contact 25 and so re-establishes the circuit of the feed solenoid 10. The previously described grinding operation on the work piece is now resumed until the next striker 23 comes into action and causes the grinding wheel to be again moved to the trimming position, the process being repeated until the grinding operation is completed.

In order that the attendant may be warned when the grinding operation is approaching completion, I arrange in association with the dial t another switch. This is located within the dial (see Figures 5 and 7) and it comprises a pair of contacts 40, 41, and a pivoted contact member 42 loaded by a spring 43. Also to the inside of the dial are secured at appropriate positions a pair of strikers 44, 45. The striker 44 extends beyond the inner periphery 46 of the dial t and the striker 45 has a recessed inner end as shown. The member 42 is operable by a plunger 47 which bears at one end against the said periphery 46 and at the other end against the member 42. When the dial t reaches the position at which the final trimming operation is to be effected the striker 44 causes the plunger 47 to move the member 42 on to the contact 40. This closes a circuit containing any convenient warning device such as a lamp which announces to the attendant that the final trimming stage has been reached. When the last striker 23 comes into action the striker 45 allows the plunger 47 to move, so that the spring 43 can move the member 42 onto the contact 41. This closes a circuit containing another warning device such as a lamp which announces that the grinding operation is completed. At the same time the last striker 23 causes the slide b to be retracted to the trimming position in readiness for commencement of operations on the next work piece to be inserted in the machine. Before the operations above described are repeated on the next work piece, the attendant by means of the handle 6 on the dial t, turns the dial back to its initial position which is determined by the abutment of a stop 50 on the dial against a fixed stop 51 situated adjacent to the part 31, the stop 51 serving also to support the said part 31 in its normal position under the pressure of the spring 32.

By this invention the feed movements of the machine, and the determining of the grinding wheel trimming periods are effected automatically in a simple and satisfactory manner, enabling increased output and greater uniformity of quality to be obtained from machines of the kind specified as compared with earlier machines which have been under the sole control of the attendant.

Having thus described my invention what I

claim as new and desire to secure by Letters Patent is:

1. In a gear wheel grinding machine of the kind specified, the combination with a headstock, a slide movable vertically in the headstock, a work spindle carried by the slide, a manually operable screw for moving the slide in the headstock, and an index plate carried by the work spindle, of an intermittently operable feeding mechanism for imparting feed movements to the slide independently of the said screw, means consisting in part of an electromagnet for actuating the feeding mechanism, and means responsive to rotational movements of the work spindle for controlling the said electromagnet.
2. In a gear wheel grinding machine as claimed in claim 1, the combination with the feeding mechanism of electrical contact devices for determining the grinding wheel trimming periods.
3. In a gear wheel grinding machine as claimed in claim 1, the combination with the slide of a crank arm in pivotal connection with the slide, a link having one end in pivotal connection with the crank arm, the axes of the two said connections being eccentric with respect to each other, and means effecting pivotal connection between the other end of the link and the screw.
4. In a gear wheel grinding machine having the features claimed in claim 1, the combination of a crank arm in pivotal connection with the slide, a link having one end in pivotal connection with the crank arm, the axis of the two connections being eccentric with respect to each other, means for effecting pivotal connection between the other end of the link and the screw, a peripherally notched disc, a pawl for imparting intermittent angular movements to the disc, means for transmitting movements from the disc to the crank arm, a solenoid for moving the pawl in one direction, and a spring for moving the pawl in the opposite direction.
5. In a gear wheel grinding machine having the features claimed in claim 1, the combination of a crank arm in pivotal connection with the slide, a link having one end in pivotal connection with the crank arm, the axes of the two connections being eccentric with respect to each other, means for effecting pivotal connection between the other end of the link and the screw, a peripherally notched disc, a pawl for imparting intermittent angular movements to the disc, means for transmitting movements from the disc to the crank arm, a solenoid for moving the pawl in one direction, a spring for moving the pawl in the opposite direction, a pinion associated with the disc, a slidable rack in engagement with the pinion, and means interconnecting the rack and crank arm.
6. In a gear wheel grinding machine having the features claimed in claim 1, the combination of a crank arm in pivotal connection with the slide, a link having one end in pivotal connection with the crank arm, the axes of the two connections being eccentric with respect to each other, means for effecting pivotal connection between the other end of the link and the screw, a peripherally notched disc, a pawl for imparting intermittent angular movements to the disc, means for transmitting movements from the disc to the crank arm, a solenoid for moving the pawl in one direction, a spring for moving the pawl in the opposite direction, a pinion associated with the disc, a slidable rack in engagement with the pinion, means interconnecting the rack and crank arm,

and manually operable means for putting the pawl out of action.

7. In a gear wheel grinding machine having the features claimed in claim 1, the combination of a crank arm in pivotal connection with the slide, a link having one end in pivotal connection with the crank arm, the axes of the two connections being eccentric with respect to each other, means for effecting pivotal connection between the other end of the link and the screw, a peripherally notched disc, a pawl for imparting intermittent angular movements to the disc, means for transmitting movements from the disc to the crank arm, a solenoid for moving the pawl in one direction, a spring for moving the pawl in the opposite direction, a solenoid controlling switch, and means associated with the work spindle for closing the switch at the end of each complete rotation of the index plate.

8. In a gear wheel grinding machine having the features claimed in claim 1, the combination of a crank arm in pivotal connection with the slide, a link having one end in pivotal connection with the crank arm, the axes of the two connections being eccentric with respect to each other, means for effecting pivotal connection between the other end of the link and the screw, a peripherally notched disc, a pawl for imparting intermittent angular movements to the disc, means for transmitting movements from the disc to the crank arm, a solenoid for moving the pawl in one direction, a spring for moving the pawl in the opposite direction, a solenoid controlling switch, and a striker on the index plate for closing the switch at the end of each complete rotation of the index plate.

9. In a gear wheel grinding machine having the features claimed in claim 1, the combination of a crank arm in pivotal connection with the slide, a link having one end in pivotal connection with the crank arm, the axes of the two connections being eccentric with respect to each other, means for effecting pivotal connection between the other end of the link and the screw, a peripherally notched disc, a pawl for imparting intermittent angular movements to the disc, means for transmitting movements from the disc to the crank arm, a solenoid for moving the pawl in one direction, a spring for moving the pawl in the opposite direction, a dial associated with the disc, a series of strikers carried by the dial, and a switch operable by the strikers for determining the trimming periods.

10. In a gear wheel grinding machine having the features claimed in claim 1, the combination of a crank arm in pivotal connection with the slide, a link having one end in pivotal connection with the crank arm, the axes of the two

connections being eccentric with respect to each other, means for effecting pivotal connection between the other end of the link and the screw, a peripherally notched disc, a pawl for imparting intermittent angular movements to the disc, means for transmitting movements from the disc to the crank arm, a solenoid for moving the pawl in one direction, a spring for moving the pawl in the opposite direction, a dial associated with the disc, a series of strikers carried by the dial, and a switch operable by the strikers for determining the trimming periods, the switch being also adapted to control the solenoid.

11. In a gear wheel grinding machine having the features claimed in claim 1, the combination of a crank arm in pivotal connection with the slide, a link having one end in pivotal connection with the crank arm, the axes of the two connections being eccentric with respect to each other, means for effecting pivotal connection between the other end of the link and the screw, a peripherally notched disc, a pawl for imparting intermittent angular movements from the disc to the crank arm, a solenoid for moving the pawl in one direction, a spring for moving the pawl in the opposite direction, a dial associated with the disc, a series of strikers carried by the dial, a switch operable by the strikers for determining the trimming periods and controlling the solenoid, a plunger for imparting movements from the strikers to the switch, a pivoted member carrying the plunger, and a solenoid connected to the said member for retracting the plunger from the striker by which the plunger has previously been actuated.

12. In a gear wheel grinding machine having the features claimed in claim 1, the combination of a crank arm in pivotal connection with the slide, a link having one end in pivotal connection with the crank arm, the axes of the two connections being eccentric with respect to each other, means for effecting pivotal connection between the other end of the link and the screw, a peripherally notched disc, a pawl for imparting intermittent angular movements to the disc, means for transmitting movements from the disc to the crank arm, a solenoid for moving the pawl in one direction, a spring for moving the pawl in the opposite direction, a dial associated with the disc, a series of strikers carried by the dial, a switch operable by the strikers for determining the trimming periods, another switch associated with the dial and adapted to control the circuits of warning devices, and strikers on the dial for actuating the latter switch when the grinding operation is approaching completion.

ARTHUR HITCHCOCK ORCUTT.
